UNITED STATES PATENT OFFICE

155,710

DESIGN FOR A CAPPED COLLAPSIBLE TUBE

Albert H. Jung, Flushing, N. Y., assignor to Victor Industries Corporation, Brooklyn, N. Y., a corporation of New York

Application September 8, 1947, Serial No. 141,267

Term of patent 14 years

(Cl. D58—17)

To all whom it may concern:

Be it known that I, Albert H. Jung, a citizen of the United States and resident of Flushing, county of Queens, city and State of New York, have invented a new, original, and ornamental Design for a Capped Collapsible Tube, of which the following is a specification, reference being had to the accompanying drawing, forming a part therein, wherein:

Fig. 1 is a side elevational view of a capped collapsible tube, showing my new design.

Fig. 2 is a top plan view thereof.

Fig. 3 is a perspective view of the cap of the capped collapsible tube, as it appears removed from the tube.

Fig. 4 is a fragmentary perspective view of the upper part of the collapsible tube as it appears with the cap removed therefrom.

The dominant features of my design reside in the portion shown in full lines and the characteristic feature is the conoidal and upwardly convex shape of the upper part of the lateral surface of the tube which merges into and forms a continuation of the lateral surface of the cap to present a bullet-like appearance at the upper

end of the tube, which is interrupted by vertical spaced ribs arranged annularly about the lower portion of the cap all as shown in the drawing.

I claim:

The ornamental design for a capped collapsible tube, substantially as shown and described.

ALBERT H. JUNG.
